UNITED STATES PATENT OFFICE

PAUL H. HORWITT, OF HARTSDALE, NEW YORK

DESIGN FOR AN AUTOMOBILE

Application filed September 13, 1930. Serial No. 36,960. Term of patent 14 years.

To all whom it may concern:

Be it known that I, PAUL H. HORWITT, a citizen of the United States of America, residing in the town of Hartsdale, in the county of Westchester and State of New York, have invented a certain new, original, and ornamental Design for an Automobile, of which the following is a specification, reference being had to the accompanying drawing, forming part thereof.

In the drawing, Figure 1 is a side elevation of an automobile with my new body design; and Figure 2 is a front end view of same.

What I claim is:

The ornamental design for an automobile as shown.

This specification signed at New York city, in the county and State of New York, this 10th day of September, 1930.

PAUL H. HORWITT.
